UNITED STATES PATENT OFFICE.

WILLIAM S. HAMM, OF HUBBARD WOODS, AND WILBER F. STEWART, OF CHICAGO,
ILLINOIS, ASSIGNEES TO THE ADAMS & WESTLAKE COMPANY, OF CHICAGO,
ILLINOIS, A CORPORATION OF ILLINOIS.

DEVICE FOR FORMING, ASSEMBLING, AND HOLDING SHEET-METAL FORMS.

1,309,088.

Specification of Letters Patent.

Patented July 8, 1919.

Application filed April 24, 1916. Serial No. 93,169.

To all whom it may concern:

Be it known that we, WILLIAM S. HAMM and WILBER F. STEWART, residents, respectively, of Hubbard Woods, county of Cook, 5 State of Illinois, and Chicago, county of Cook, State of Illinois, and citizens of the United States, have invented, jointly, certain Improvements in Devices for Forming, Assembling, and Holding Sheet-Metal 10 Forms, of which the following is a specification, and which are illustrated in the accompanying drawings, forming a part thereof.

The invention relates to devices for assembling and holding for subsequent operations 15 thereon sheet metal forms; its object being to provide for convenience and accuracy in assembling sheet metal parts, particularly when the same are to be united by a soldering operation, and it consists broadly in a 20 ring having an internal annular channel for receiving and positioning a band, a seat adjacent the channel for receiving and positioning a cylindrical part, and having other specific features as hereinafter described.

25 In the accompanying drawings,

Figures 1, 3 and 5 are plan views of the device showing three somewhat different forms;

30 Figs. 2 and 4 are sectional views on the lines 2—2 and 4—4, respectively, of Figs. 1 and 3;

Fig. 6 is a sectional view, partly in elevation, of the form shown in Fig. 5 taken on the line 6—6 of Fig. 5.

35 Fig. 7 is a detail of the band which the device is adapted to receive; and

40 Fig. 8 is a central transverse sectional view of the several forms of construction, the sheet metal forms adapted to be assembled and held thereby being shown partly in section.

In all of the different forms of construction the device comprises a main ring 10, having at one edge an instanding flange 11, 45 its opposite edge being beveled inwardly, as shown at 12. The inner circumferential surface 13 of the ring 10 is parallel to its axis.

A second ring 14 of somewhat less diameter than the internal diameter of the ring 10, 50 and also of less axial width than that ring, is provided with an instanding or radial flange 15, which is seated upon and secured to the flange 11, the two rings being concentrically disposed and the space between

them forming a channel for receiving a 55 band, such as 16, constituting one of the sheet metal forms to be assembled and held. The edge 17 of the ring 14, opposite to that from which the flange 15 projects, is radially flat and forms a shoulder upon which may 60 be seated the end of a cylindrical sheet metal form 18, to which the band 16 is adapted to be soldered.

The inner margin of the beveled face 12 of the ring 10 is spaced from the inner 65 radial face of the flange 11 a distance as great, and preferably the same, as the width of the band 16. The two sheet metal forms being seated within the holder, as shown in Fig. 8, the band 16 overlaps to some extent 70 the outer wall of the cylindrical form 18, the extent of this overlapping being determined by the difference in the axial width of the ring 14 and the width of the band.

The sheet metal forms being thus 75 assembled and held within the device, particles of solder in solid form may be dropped into the channel bounded by the outer surface of the cylindrical form 18 and the beveled face 12 of the ring 10. Heat being 80 applied, this solder is melted and flows between the band 16 and the cylinder. The assembling and holding device is made of a metal which will endure the heat necessary to the soldering operation and to which the 85 solder will not adhere.

When the band 16 is intended to be subsequently stripped from the cylinder, it is provided with a tag 19 at one end and the holding device is provided with a recess, as 20, 90 for receiving this tag and holding it away from the body portion of the band in order that it may not be soldered thereto. The ring 10 is provided in its outer face with a boss 21 within which the recess is formed, 95 in the construction illustrated in Fig. 1.

In the form of construction illustrated in Fig. 3, the recess for receiving the tag 19 takes the form of a channel extending through the boss 21 and the body of the ring 10, and being tangential to the inner wall 13 of this ring.

In the construction shown in Fig. 5, the recess takes the form of a tangential channel 23 extending through the body of the 105 ring 10, and the outer face 24 of the boss 21 is continued in line with this channel and may have at its outer end a shoulder 25

against which the end of the tag is seated, thereby properly positioning the band within the holder.

In the use of the forms shown in Figs. 1 and 5, the band is inserted axially within the channel between the rings 10 and 14, its tag entering the recess or channel 20 or 23. When the holder takes the form illustrated in Fig. 3, the band may be inserted 10 lengthwise through the channel 21 and into the channel between the two rings.

The device is made of two parts secured together for convenience of manufacture. When secured together, as by means of 15 screws, as shown, the two rings form a unitary structure.

In the use of the device it is the practice to pass it and the forms to be united, when 20 assembled therein, through a heated chamber for the purpose of melting the solder.

While preferable forms of the device are shown, various changes in detail may be made without departing from the scope of the invention. Although the device is 25 shown as circular in form, its shape will, of course, conform to that of the articles in connection with which it is to be used, whether they be circular, oblong, or of other configuration.

30 We claim as our invention—

1. A device for soldering lap joints comprising a seat for the article to be soldered, a ring for tightly encircling the upper margin of the overlapping member of the joint 35 adapted to extend to its upper edge, the

upper face of the ring flaring outwardly from the line of contact with the article, whereby when the article is in place a channel will be provided having as its bottom the upper edge of the overlapping member 40 of the joint.

2. A device for soldering lap joints comprising a seat for the inner member of the joint, a seat for the outer member of the joint, a ring for tightly encircling the upper 45 margin of such outer member and having an upper flaring face.

3. A soldering tool comprising a wall conforming in outline to the article to be soldered and having an inner face forming a bearing surface for the article and adapted to extend to its upper edge, the upper margin 50 of the wall flaring outwardly to form with the article a channel for the reception of solder.

4. An assembling and holding device for sheet metal forms comprising, in combination, a ring having its inner face parallel to its axis, an instanding radial flange at one margin and its other margin outwardly 60 flared, an inner concentric ring seated upon and secured to the flange and having its outer face parallel with and spaced apart from the inner face of the first-named ring, the width of the inner ring being less than 65 the inner straight portion of the outer ring, the outer ring having a channel through its body portion tangential to its inner face.

WILLIAM S. HAMM.
WILBER F. STEWART.
